SIGNAL REPRODUCING SYSTEM

Jack Sharpe, Wembley, England

Application November 1, 1945, Serial No. 626,117
In Great Britain November 1, 1944

13 Claims. (Cl. 315—22)

1

This invention relates, in general, to signal-reproducing systems. It is especially directed to systems for reproducing and distinguishing between a first periodic signal which recurs at a substantially constant repetition frequency in a given time interval and a second signal which does not recur at the same repetition frequency throughout the same time interval. The invention, while subject to a variety of applications, is particularly suited for use in a radio-locating system and will be described in detail in that connection.

One prior radio-locating system of the type under consideration comprises a directional transmitting and receiving system for exploring or searching an area in space to derive an output signal in the event that one or more reflecting objects are within the space scanned. The searching process entails scanning the space in question with signal energy in a uniform scanning pattern and at fixed scanning frequencies. The scanning may be similar to that well understood from television practice wherein an area is scanned in a plurality of fields each of which includes a relatively large number of scanning lines. The output signal, denoting the presence of a reflecting object in the scanned space, constitutes a reflection of the transmitted energy occasioned by the reflecting object and intercepted by the receiving component of the system. This output signal is applied to a cathode-ray indicating device which is controlled to scan a target, such as a picture-reproducing screen of the fluorescent type, in synchronism with the scanning of the explored space. The applied signal modulates the cathode-ray beam to establish on the target an indication of the position of the reflecting object in the scanned space.

When a stationary object is encountered, repeated field scanning of the explored space over a given time interval produces one related output signal occurring at a constant repetition frequency corresponding to the field-scanning frequency. This signal establishes repeated indications in the same part of the target of the indicating device from which an observer is able to discern the stationary object. However, a relatively fast-moving object in the explored space causes a different or second output signal to be obtained from the receiver. The second signal recurs at a varying frequency determined by the speed of movement of the object with relation to the scanning times. It controls the indicating device to establish indications on different parts of its target during succeeding field scans from which

2

an observer may detect the presence of the moving object.

Arrangements of the type described have proved to be satisfactory but are subject to the limitation that they require prolonged observation of the target of the indicating device to distinguish stationary and moving objects in the explored space. This is so because the target picture is composed of the same colors in each case and differentiation of stationary and moving objects is based upon the movement of a portion of the picture in repeated field scans. In some installations, where it is desired to distinguish between moving and stationary objects at a glance at the picture pattern, this limitation may be objectionable.

Another radio locator forms the subject matter of copending application Serial No. 626,148, filed November 1, 1945, in the names of Leslie C. Jesty et al., and assigned to the same assignee as the present invention. This other arrangement includes a signal-reproducing system having fluorescent means adapted to emit visible light of one color when repeatedly excited a predetermined plurality of times but adapted to emit visible light of a contrasting color when excited for a lesser number of times. It has the advantage of displaying stationary or relatively slow-moving reflecting objects in one color while indicating fast-moving objects in a different color. Such a system requires repeated scanning of an area in space for at least the aforementioned predetermined plurality of times to produce a multicolor picture pattern. In some installations it may be desirable to obtain such a multicolor picture pattern more quickly.

It is an object of the present invention, therefore, to provide a signal-reproducing system which substantially avoids the aforementioned limitations of the described arrangements.

It is another object of the invention to provide an improved system for reproducing and distinguishing between two signals, one of which recurs at a substantially constant repetition frequency in a given time interval while the other does not recur at the same repetition frequency throughout the same time interval.

It is a specific object of the invention to provide an improved signal-reproducing system especially suited for application to radio-locating systems and adapted quickly to distinguish between stationary and moving objects or between relatively slow-moving and relatively fast-moving objects.

55 In accordance with the invention, a system for

reproducing and distinguishing between a first periodic signal which recurs at a substantially constant repetition frequency in a given time interval and a second signal which does not recur at the same repetition frequency throughout the same time interval comprises fluorescent signal-reproducing means. The signal-reproducing means is adapted to emit visible light of one predominant color when excited for a given excitation period with incident energy within a first amplitude range or when repeatedly excited at the aforesaid repetition frequency for a certain number of such given excitation periods with incident energy within a second and lower amplitude range. It is also adapted to emit visible light of a contrasting color when excited for a lesser number of such excitation periods with incident energy within the second amplitude range. The system has means for effectively scanning the signal-reproducing means at the aforesaid repetition frequency during the above-mentioned time interval with excitation energy representing the first and second signals. The scanning process is such as to excite elemental areas of the signal-reproducing means in any one scanning cycle for an interval at least equal to the aforesaid given excitation period. Means are also provided for adjusting the amplitude levels of the excitation energy during one scanning cycle within the given time interval to values within the first-mentioned amplitude range and during another scanning cycle within this given time interval to values within the second-mentioned or lower amplitude range.

For a better understanding of the present invention, together with other and further objects thereof, reference is had to the following description taken in connection with the accompanying drawing, and its scope will be pointed out in the appended claims.

In the drawing, Fig. 1 is a schematic representation of a radio-locating system embodying the present invention in one form; and Figs. 2a and 2b are views of one component of the Fig. 1 arrangement.

Referring now more particularly to Fig. 1, there is represented a radio locator including a signal-reproducing system in accordance with the instant invention. The locator arrangement, as illustrated, includes a space-scanning and reflected-signal-receiving system 10 represented in block form. There is associated with unit 10 a directive transmitting antenna system which, in order to simplify the drawing, is represented by a dipole antenna 11 and a parabolic reflector 11a. A receiving antenna system, having similar directive properties, is also associated with unit 10 and is indicated by a dipole 12 and a parabolic reflector 12a. An ultra-short-wave signal generator is included in unit 10 for energizing antenna 11. The generator usually operates in the ultra-short-wave range since short-wave signals are most easily directed and most readily reflected by reflecting objects. Unit 10 also has suitable means for controlling antenna system 11 so that the directed signal energy transmitted thereby scans a portion of space in a series of fields of parallel lines at constant line-scanning and field-scanning frequencies. The scanning elements additionally control antenna 12 in synchronism with the transmitting antenna to intercept reflections of the transmitted signal energy which may be caused by reflecting objects positioned within the scanned space.

A synchronous deflecting-signal generator 13

is coupled to unit 10, as indicated by construction lines 14 and 15 extending between parts *a* and *b* of unit 10 and parts *c* and *d* of unit 13. Where the space scanning effected by unit 10 is in the form of a series of fields of parallel lines, unit 13 includes elements for generating two deflecting signals. These deflecting signals may be termed the line- and field-scanning signals. The intercoupling of units 10 and 13 is such that the line- and field-scanning signals generated are synchronized with and correspond to the line and field scanning, respectively, of antenna systems 11 and 12. This interconnection varies with the type of apparatus utilized in units 10 and 13. Where antenna systems 11 and 12 are mechanically controlled to accomplish desired line- and field-scanning functions, the interconnection may be mechanical and the synchronous generator may be mechanically controlled in synchronism with the antenna scanning. On the other hand, for electrical control of the scanning operations of the antenna systems, generator 13 may produce deflecting signals applied through the connection 14 and 15 to control the antenna systems in synchronism with the generated signals.

A suitable arrangement for elements 10-15, inclusive, is illustrated in United States Letters Patent 2,231,929, issued February 18, 1941, to Joseph Lyman. In the reference patent, space scanning is accomplished by a pair of transmitting antennas. One antenna radiates a vertical ribbon of signal energy which is swept horizontally at a desired field-scanning frequency. The other transmits a horizontal ribbon of signal energy which is swept vertically at a line-scanning frequency, thirty or more times that of the field scanning. A corresponding pair of directive receiving antennas are provided, each moving synchronously with one of the transmitting antennas. The scanning for all antennas is accomplished by mechanically driving a parabolic reflector associated with each. The receiver coupled to the receiving antennas includes an amplitude-delayed detector which produces an output signal only during time intervals when reflected signal energy is received concurrently by each of the receiving antennas. The synchronous deflecting-signal generator of the reference patent includes a pair of adjustable resistor arrangements for producing line- and field-scanning signals synchronized with the corresponding components of the space scanning. The adjustable element of one resistor is driven with the line-scanning antennas, while the adjustable element of the other is driven with the field-scanning antennas. To this end, a mechanical interconnection is provided between the antennas and the adjustable elements of the resistors.

The radio locator of Fig. 1 of the present invention further includes a system for reproducing and distinguishing between a first periodic signal which recurs at a substantially constant repetition frequency in a given time interval and a second signal which does not recur at this same repetition frequency throughout the same time interval. This system comprises fluorescent signal-reproducing means adapted to emit visible light of one predominant color when excited for a given excitation period with incident energy within a first amplitude range or when repeatedly excited at the aforesaid repetition frequency for a certain number of such given excitation periods with incident energy within a second and lower amplitude range. It is also adapted to emit visible light of a contrasting color when

excited for a lesser number of times with incident energy within the lower amplitude range.

More specifically, the signal-reproducing means comprises a fluorescent screen constituting the target area of a cathode-ray tube 20. The screen includes a glass carrier 21 and superposed fluorescent portions or layers adapted to emit visible light of contrasting colors. The first layer 22 fluoresces fully when excited for a given excitation period with energy within a first amplitude range. It has an afterglow period long with reference to the period corresponding to the repetition frequency of the repeating signal to be reproduced so that recurrent excitation at this frequency produces cumulative fluorescent effects. It has an excitation build-up period such that substantial fluorescence is also obtained when the layer is repeatedly excited a certain number of times, defined more particularly hereinafter, with incident energy within a second but lower amplitude range. The second layer 23 has an afterglow period less than, but preferably almost equal to, the period of the applied repeating signal. It has an excitation build-up characteristic such that substantial fluorescence is obtained when it is excited for a lesser number of times but, preferably, when excited for only a single one of the aforementioned given excitation periods with incident energy within either the first or second amplitude ranges referred to. Each of these layers, preferably, has excitation and afterglow characteristics such that the rates of build-up of fluorescence and decay of afterglow vary with the intensity of the excitation energy applied thereto. Layer 22 is substantially transparent to the light emitted by layer 23, enabling the fluorescence of each to be viewed from a single side of screen 21. Additionally, layer 23 has energy-translating properties such that incident energy applied thereto is partially translated to the alternate layer, permitting the excitation of both from the opposite side of the composite screen structure. The method of fabricating this screen, as well as suitable fluorescent materials which may be included therein, is given herein-after.

The signal-reproducing system under consideration has means for effectively scanning the screen of tube 20 at the repetition frequency of the first-mentioned periodic signal with excitation energy in such a manner as to excite elemental areas of each layer or portion of the screen in any one scanning cycle for an interval at least equal to the given excitation period referred to in the preceding paragraph. Since the screen is illustrated as the target area of cathode-ray tube 20, the exciting means includes a conventional electrode system for producing a cathode-ray beam but a potential source 27 normally biases the tube to cutoff. A pair of horizontal deflecting plates 30 and 31 are coupled to one output circuit of unit 13 for deflecting the beam of cathode-ray tube 20 in a horizontal direction synchronously with the horizontal-scanning antenna of unit 10. Vertical deflecting plates 32 and 33 are coupled to a second output circuit of unit 13 to deflect the cathode-ray beam synchronously with the vertical-scanning antenna of unit 10.

The beam of tube 20 may be controlled by a brilliancy-control electrode 35. The signal output of the receiver portion of unit 10 is applied to this electrode to overcome the tube bias and supply beam energy modulated in accordance with and representing the signal output thereof.

To this end, electrode 35 is coupled to unit 10 through a condenser 36 and a variable-gain amplifier 37. A potential-dividing resistor 38 is provided for controlling the gain characteristic of the amplifier. Adjustable taps 39 and 40 of the potential-dividing resistor are associated with commutator means 41 for adjusting the amplitude levels of the beam energy of tube 20 during one scanning cycle to values within a first amplitude range and during another scanning cycle to values within a second and lower amplitude range. Commutator 41 is shown in block form, partially broken away to reveal segments 42 and 43 connected in circuit with taps 39 and 40 through co-operating brushes 44 and 45, respectively.

Plan views of segments 42 and 43 are represented in Figs. 2a and 2b, respectively. The former has one quadrant 42a of conductive material and a remaining section 42b of insulating material. The latter has a quadrant 43b of insulating material and the remainder 43a is of conductive material. Both are secured to a shaft 46 and so oriented that sections 42a and 43b are in axial alignment. The segments are connected through shaft 46 in circuit with a slip ring 47 and co-operating brush 48. A coupling, indicated by construction lines 50 and 51 extending between parts a and b of unit 10 and parts e and f of commutator 41, provides a driving connection for shaft 46. This interconnection, where the space-scanning arrangement is in the form of the above-identified patent, comprises a mechanical linkage for rotating the commutator in synchronism with the field-scanning process. With the particular segment construction illustrated, the coupling includes a step-down gear train (not shown) to drive the commutator at one-fourth the field-scanning frequency.

In adjusting the described radio locator, tap 39 is set to establish such a high gain for amplifier 37 that signals applied therethrough to control electrode 35 with this amplification produce a beam intensity in tube 20 within a high amplitude range, effective to excite both layers of screen 21-23 to substantially full fluorescence in a single field scan. Tap 40, on the other hand, is adjusted to establish a reduced amplifier gain so that signals translated with the reduced gain produce a beam intensity in tube 20 within a lower amplitude range, effective to excite only layer 23 of the screen to substantial fluorescence in a single field scan.

Let it be assumed that layers 22 and 23 of the screen emit green and red light, respectively; that layer 22 has a build-up period for intensities of the cathode-ray beam within the reduced amplitude range such as to require repeated excitation during at least five consecutive field scans to attain substantial fluorescence; and that layer 23 produces substantially full fluorescence in response to each field scan of the cathode-ray beam, even those in which the beam intensity is within the reduced amplitude range. Further assume that unit 10 repeatedly scans an area in space during a time interval in which both a stationary and a relatively fast-moving reflecting object are included within the scanned space. For the assumed conditions, a composite output signal is obtained from the receiver portion of unit 10. It includes a first periodic signal, repeating at the field-scanning frequency and occurring during that portion of each field scan when the transmitted energy is incident upon the stationary reflecting object. The composite signal also in-

cludes a second signal which does not repeat at the field-scanning frequency because the position of a fast-moving object in the scanned space changes materially from one field scan to the next. The receiver output signal is translated through amplifier 37 to brilliancy-control electrode 35, producing in tube 28 a modulated cathode-ray beam representing both the first and second signals. The deflecting elements 30-31 and 32-33, under the control of synchronous generator 13, scan screen 21-23 with the modulated cathode-ray beam in synchronism with the space scanning, exciting elemental areas thereof in any one scanning cycle for an interval determined by the physical length of the scanning spot divided by the rate of passage of the spot across an elemental area. The beam-scanning function traces a picture pattern on the screen depicting the positions of both reflecting objects in the scanned space in the following manner.

Consider that commutator segment 42 controls the gain level of amplifier 37 during the first field-scanning period. In this operating interval the beam of tube 28 has amplitude values within a high range. It excites portions of the screen 21-23 corresponding to the positions of the reflecting objects in the scanned space. In view of the high beam intensity the resulting picture pattern is predominantly green, the characteristic color of layer 22 which has the longer afterglow and hence the slower rate of decay of fluorescence. For the next three succeeding scanning intervals commutator segment 43 causes amplifier 37 to have a reduced gain, resulting in a beam intensity of amplitude levels in a lower range of values. In each of these three succeeding scans the first signal, representing the stationary object, partially restores the decaying fluorescence of that part of layer 22 which designates this object, thereby to maintain the representation of the stationary object in green light. However, the second signal, representing the fast-moving object, excites different parts of the screen in each of the three scans under consideration. In general, it excites parts of the screen that have not previously been excited and because of the reduced beam intensity produces a traveling light spot of red color, characteristic of layer 23 which alone is energized to substantial fluorescence in a single scan by the beam of reduced intensity.

In still further field-scanning intervals, the excitation of the screen is cyclically varied by commutator 41, as described above. That is, in one field scan all reflecting objects are displayed predominantly in a green color pattern and in the next three succeeding scans the stationary object is continuously shown in a green color while the representations of fast-moving objects fade away from green and appear in red. Thus, by observation of the screen the presence of stationary and relatively fast-moving objects may be discerned and distinguished. Where a relatively slow-moving object is in the scanned space, the related signal component of the composite output signal of unit 16 occurs at approximately the field-scanning frequency and produces a substantially green indication of this object on the screen.

It will be apparent that the commutator segments of unit 41 may be proportioned in any desired manner. The illustration of Figs. 2a and 2b is given only by way of example. In the limiting case these segments have equal conductive and insulating portions. When so constructed and rotated at half the field frequency, they cause the beam of tube 28 to have values within high-

and low-amplitude ranges in alternate field-scanning intervals. For such operation, stationary objects are again displayed in green light but fast-moving objects are designated by alternate red and green light spots, traversing the screen at a rate governed by the speed of movement of the moving object within the scanned space.

In constructing fluorescent screens of the type provided for tube 28, it is not necessary that the several layers be entirely discrete. One may merge into the other but it is preferable that there be a preponderance of one fluorescent mixture emitting light of a desired color on one surface of each layer. For example, a preponderance of one material should be provided at the face of layer 22 adjacent carrier 21 and a preponderance of the other at the face of layer 23 closest to the cathode of the electron-gun structure. Either or both layers may be composed of a mixture of two or more fluorescent compounds to obtain a desired visible color.

A screen of the type discussed above may be fabricated in the following manner. A first layer of fluorescent powder is dusted upon the glass carrier which is previously covered with a thin binder layer consisting of a solution of phosphoric acid in acetone. The thickness of this layer is arranged in accordance with a desired per cent. optical transmission thickness. An "optical transmission thickness of given percentage" means that this percentage of a normally incident beam of parallel light rays penetrates the layer. The second layer may be applied by spraying over the first layer a dilute solution of potassium silicate and thereafter depositing a second fluorescent powder with a dry powder spray to the desired optical thickness. Succeeding layers, if utilized, may be applied in the same way as the second.

The screen in one form may include, as layer 22, green fluorescing calcium-magnesium tungstate activated with uranium and having an optical transmission thickness of 30 per cent. Its layer 23 may include red fluorescing calcium phosphate activated with samarium and having an optical transmission thickness of 55 per cent. Other suitable screen compositions are recited in the above-mentioned copending application of Jesty et al. The arrangement of the copending application is generally similar to that here described and, for the most part, corresponding components thereof are identified by the same reference characters. It will be apparent that the screen constructions of the other application are suitable for use in the reproducing system forming the subject matter of the present invention.

While there has been described what is at present considered to be the preferred embodiment of this invention, it will be obvious to those skilled in the art that various changes and modification may be made therein without departing from the invention, and it is, therefore, aimed in the appended claims to cover all such changes and modifications as fall within the true spirit and scope of the invention.

What is claimed is:

1. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to

emit visible light of one predominant color when excited for a given excitation period with incident energy within a first amplitude range or when repeatedly excited at said repetition frequency for a certain number of said given excitation periods with incident energy within a second lower amplitude range but adapted to emit visible light of a contrasting color when excited for a lesser number of said excitation periods with incident energy within said second amplitude range, means for effectively scanning said signal-reproducing means at said repetition frequency during said time interval with excitation energy representing said first and second signals so as to excite elemental areas thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

2. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to emit visible light of one color when excited for a given excitation period with incident energy within a first amplitude range or when repeatedly excited at said repetition frequency for a certain number of said given excitation periods with incident energy within a second lower amplitude range but adapted to emit visible light of a contrasting color when excited by incident energy within said second amplitude range for only said given excitation period, means for effectively scanning said signal-reproducing means at said repetition frequency during said time interval with excitation energy representing said first and second signals so as to excite elemental areas thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

3. A system for reproducing and distinguishing between a first periodic signal which recurs at a substantially constant repetition frequency in a given time interval and a second signal which does not recur at said repetition frequency throughout said time interval comprising, a fluorescent screen adapted to emit visible light of one predominant color when excited for a given excitation period with incident energy within a first amplitude range or when repeatedly excited at said repetition frequency for a certain number of said given excitation periods with incident energy within a second lower amplitude range but adapted to emit visible light of a contrasting color when excited for a lesser number of said excitation periods with incident energy within said second amplitude range, means for effectively scanning said screen at said repetition frequency during said time interval with excitation energy representing said first and second signals so as to excite elemental areas thereof in any one scanning cycle for an interval at least equal to said given excitation period, and means for adjusting

the amplitude levels of said excitation energy during one scanning cycle within said given time interval to values within said first amplitude range and during another scanning cycle within said given time interval to values within said second amplitude range.

4. A system for reproducing and distinguishing between a first periodic signal which recurs at a substantially constant repetition frequency in a given time interval and a second signal which does not recur at said repetition frequency throughout said time interval comprising, signal-reproducing means including first and second fluorescent portions, said first portion being adapted to emit visible light of one color when excited for a given excitation period with incident energy within a first amplitude range or when repeatedly excited at said repetition frequency for a certain number of said given excitation periods with incident energy within a second lower amplitude range, said second portion being adapted to emit visible light of a contrasting color when excited for a lesser number of said excitation periods with incident energy within said second amplitude range, means for effectively scanning said signal-reproducing means at said repetition frequency during said time interval with excitation energy representing said first and second signals so as to excite elemental areas of each of said portions thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

5. A system for reproducing and distinguishing between a first periodic signal which recurs at a substantially constant repetition frequency in a given time interval and a second signal which does not recur at said repetition frequency throughout said time interval comprising, a screen including first and second superposed fluorescent portions, said first portion being adapted to emit visible light of one color when excited for a given excitation period with incident energy within a first amplitude range or when repeatedly excited at said repetition frequency for a certain number of said given excitation periods with incident energy within a second lower amplitude range, said second portion being adapted to emit visible light of a contrasting color when excited for a lesser number of said excitation periods with incident energy within said second amplitude range, one of said portions being substantially transparent to the light emitted by the other, means for effectively scanning said screen at said repetition frequency during said time interval with excitation energy representing said first and second signals so as to excite elemental areas of each of said portions thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

6. A system for reproducing and distinguishing between a first periodic signal which recurs at a substantially constant repetition frequency in a given time interval and a second signal which

does not recur at said repetition frequency throughout said time interval comprising, a screen including first and second superposed fluorescent portions, said first portion being adapted to emit visible light of one color when excited for a given excitation period with incident energy within a first amplitude range or when repeatedly excited at said repetition frequency for a certain number of said given excitation periods with incident energy within a second lower amplitude range, said second portion being adapted to emit visible light of a contrasting color when excited for a lesser number of said excitation periods with incident energy within said second amplitude range, one of said portions having energy-translating properties such that the excitation of said one portion causes excitation of the other, means for effectively scanning said one portion of said screen at said repetition frequency during said time interval with excitation energy representing said first and second signals so as to excite elemental areas of each of said portions thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

7. A system for reproducing and distinguishing between a first periodic signal which recurs at a substantially constant repetition frequency in a given time interval and a second signal which does not recur at said repetition frequency throughout said time interval comprising, a screen including first and second superposed fluorescent portions individually having excitation and afterglow characteristics such that the rates of build-up of fluorescence and decay of afterglow vary with the intensity of the excitation energy, said first portion being adapted to emit visible light of one color when excited for a given excitation period with incident energy within a first amplitude range or when repeatedly excited at said repetition frequency for a certain number of said given excitation periods with incident energy within a second lower amplitude range, said second portion being adapted to emit visible light of a contrasting color when excited for a lesser number of said excitation periods with incident energy within said second amplitude range and having energy-translating properties such that the excitation thereof causes excitation of said first portion, means for effectively scanning said second portion of said screen at said repetition frequency during said time interval with excitation energy representing said first and second signals so as to excite elemental areas of each of said portions thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

8. A system for reproducing and distinguishing between a first periodic signal which recurs at a substantially constant repetition frequency in a given time interval and a second signal which does not recur at said repetition frequency throughout said time interval comprising, signal-reproducing means including a first fluorescent

70
75

portion having an afterglow long with reference to the period of said repetition frequency and a second fluorescent portion having an afterglow approximately equal to the period of said repetition frequency, said first portion being adapted to emit visible light of one color when excited for a given excitation period with incident energy within a first amplitude range or when repeatedly excited at said repetition frequency for a certain number of said given excitation periods with incident energy within a second lower amplitude range, said second portion being adapted to emit visible light of a contrasting color when excited for a lesser number of said excitation periods with incident energy within said second amplitude range, means for effectively scanning said signal-reproducing means at said repetition frequency during said time interval with excitation energy representing said first and second signals so as to excite elemental areas of each of said portions thereof in any one scanning cycle for an interval at least equal to said given excitation period, and means for adjusting the amplitude levels of said excitation energy during one scanning cycle within said given time interval to values within said first amplitude range and during another scanning cycle within said given time interval to values within said second amplitude range.

9. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to emit visible light of one predominant color when excited for a given excitation period with incident energy within a first amplitude range or when repeatedly excited at said repetition frequency for a certain number of said given excitation periods with incident energy within a second lower amplitude range but adapted to emit visible light of a contrasting color when excited for a lesser number of said excitation periods with incident energy within said second amplitude range, means for effectively scanning said signal-reproducing means at said repetition frequency during said time interval with excitation energy representing said first and second signals so as to excite elemental areas of each of said portions thereof in any one scanning cycle for an interval at least equal to said given excitation period, and means for adjusting the amplitude levels of said excitation energy during one scanning cycle within said given time interval to values within said first amplitude range and during a predetermined number of succeeding scanning cycles within said given time interval to values within said second amplitude range.

10. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to emit visible light of one predominant color when excited for a given excitation period with incident energy within a first amplitude range or when repeatedly excited at said repetition frequency for a certain number of said given excitation periods with incident energy within a second lower amplitude range but adapted to emit visible light of a contrasting color when

excited for a lesser number of said excitation periods with incident energy within said second amplitude range, means for producing a modulated cathode-ray beam representing said first and second signals and for scanning said signal-reproducing means with said beam at said repetition frequency during said time interval so as to excite elemental areas thereof in any one scanning cycle for an interval at least equal to said given excitation period, and means for adjusting the amplitude levels of said cathode-ray beam during one scanning cycle within said given time interval to values within said first amplitude range and during another scanning cycle within said given time interval to values within said second amplitude range.

11. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to emit visible light of one predominant color when excited for a given excitation period with incident energy within a first amplitude range or when repeatedly excited at said repetition frequency for a certain number of said given excitation periods with incident energy within a second lower amplitude range but adapted to emit visible light of a contrasting color when excited for a lesser number of said excitation periods with incident energy within said second amplitude range, an electrode system for producing a cathode-ray beam, means including a variable-gain amplifier for applying said first and second signals to said electrode system to modulate said beam in accordance therewith, means for scanning said signal-reproducing means at said repetition frequency during said time interval with said beam so as to excite elemental areas thereof in any one scanning cycle for an interval at least equal to said given excitation period, and means for controlling the gain characteristic of said amplifier to adjust the amplitude levels of said cathode-ray beam during one scanning cycle within said given time interval to values within said first amplitude range and during another scanning cycle within said given time interval to values within said second amplitude range.

12. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to emit visible light of one predominant color when

excited for a given excitation period with incident energy within a first amplitude range or when repeatedly excited at said repetition frequency for a certain number of said given excitation periods with incident energy within a second lower amplitude range but adapted to emit visible light of a contrasting color when excited for a lesser number of said excitation periods with incident energy within said second amplitude range, an electrode system for producing a cathode-ray beam, means including a variable-gain amplifier for applying said first and second signals to said electrode system to modulate said beam in accordance therewith, means for scanning said signal-reproducing means at said repetition frequency during said time interval with said beam so as to excite elemental areas thereof in any one scanning cycle for an interval at least equal to said given excitation period, and commutator means for controlling the gain characteristic of said amplifier to adjust the amplitude levels of said cathode-ray beam during one scanning cycle within said given time interval to values within said first amplitude range and during another scanning cycle within said given time interval to values within said second amplitude range.

13. A system for reproducing and distinguishing between a first periodic signal which recurs at a substantially constant repetition frequency in a given time interval and a second signal which does not recur at said repetition frequency throughout said time interval comprising, fluorescent signal-reproducing means adapted to emit visible light of one predominant color when excited for a given excitation period with incident energy within a first amplitude range or when repeatedly excited at said repetition frequency for a certain number of said given excitation periods with incident energy within a second lower amplitude range but adapted to emit visible light of a contrasting color when excited for a lesser number of said excitation periods with incident energy within said second amplitude range, means for effectively scanning said signal-reproducing means at said repetition frequency during said time interval with excitation energy representing said first and second signals so as to excite elemental areas thereof in any one scanning cycle for an interval at least equal to said given excitation period, and means for cyclically adjusting the amplitude levels of said excitation energy to values within said first amplitude range during at least one scanning cycle within said given time interval and to values within said second amplitude range during at least one succeeding scanning cycle within said given time interval.
